(57) **CLAIM**

The ornamental design for a pet treat as shown and described.

DESCRIPTION

FIG. 1 is a front, top and right side perspective view of a pet treat according to the new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings illustrate portions of the pet treat that form no part of the claimed design. The break lines shown in the middle portion of the pet treat indicate that the appearance of any portion of the article between the break lines forms no part of the claimed design.
